TAPE CONTROLLER FOR MAGNETIC TAPE DECKS

John H. Wilson, 6422 E. 41st St.,
Tulsa, Okla. 74135

Filed June 27, 1973, Ser. No. 374,246

Term of patent 14 years

Int. Cl. D14—02

U.S. Cl. D26—5 C

FIG. 3

FIG. 2

FIG. 4

FIG. 1

FIG. 1 is a front elevational view of a tape controller for magnetic tape decks showing my new design;

FIG. 2 is a side elevational view;

FIG. 3 is a rear elevational view; and

FIG. 4 is a top plan view thereof.

I claim:

The ornamental design for a tape controller for magnetic tape decks, substantially as shown and described.
